UNITED STATES PATENT OFFICE.

JAMES MARSDEN, OF WIGAN, ENGLAND.

DESIGN FOR A POWDER-PAD.

SPECIFICATION forming part of Design No. 29,870, dated December 27, 1898.

Application filed November 30, 1898. Serial No. 697,913. Term of patent 7 years.

To all whom it may concern:

Be it known that I, JAMES MARSDEN, a subject of Her Majesty the Queen of Great Britain, residing at Wigan, in the county of Lancaster, England, have invented and produced a new and original Design for Powder-Pads, of which the following is a specification, reference being had to the accompanying drawings, forming part thereof.

Figure 1 is a perspective view of the powder-pad, showing my new design; Fig. 2, a cross-sectional view.

As shown in the drawings, the leading or material feature of my design consists of the container or box A, hollowed out inside to form a receptacle for the powder and formed on the outside with a rim B and shoulder C.

D is an inner porous cover, and E an outer cover perforated with clean-cut holes.

F is a ring fitting on the rim B against the shoulder C, which firmly binds the outer and inner covers to the rim. 20

Having described my invention, what I claim as new, and desire to secure by Letters Patent, is— 25

The design for a powder-pad as herein shown and described.

In witness whereof I have hereunto signed my name, this 12th day of November, 1898, in the presence of two subscribing witnesses. 30

JAMES MARSDEN.
